DISPLAY DEVICE

Edward L. Fuchs, St. Louis, Mo., assignor of
one-half to William L. Fuchs, St. Louis, Mo.

Application May 15, 1933. Serial No. 671,975

3 Claims. (Cl. 40—135)

My invention relates to improvements in display devices and methods of forming the same, and more particularly to an improved advertising sign having characters or legends adapted to reflect light when rays from an external source are directed thereto.

An object of the present invention is to provide an improved method for forming a display on a base of flexible material, such as fabric, which method is simple, economical, and results in a highly effective display for advertising or kindred purposes.

Another object of the present invention is to provide an improved fabric mounted display device or sign of the type noted above, which is unusually durable and especially well adapted to withstand the deleterious effects of vibration, dirt, and moisture.

These and other objects and advantages will more clearly appear from the following description and accompanying drawing, illustrating several presently preferred embodiments of my invention.

In the drawing, Fig. 1 is a plan view showing a fabric backing member having a selected area thereof coated with a layer of thermoplastic cement; Fig. 2 illustrates the fabric backing or base member of Fig. 1, with the central portion of the cement-coated area covered with a layer 30 of light-reflecting material, and such covered portion embossed to provide an irregular light-reflecting surface; Fig. 3 is a plan view of one embodiment of my invention in finished form; Fig. 4 is a sectional view taken along the line 35 4—4 of Fig. 3, and Fig. 5 is a sectional view taken through a display device of modified construction.

Referring, now, by characters of reference to the drawing, reference numeral 10 indicates a 40 sheet of fabric, fabrikoid, or other sheet material which is to receive the display means constituting my invention, and which forms a base or mounting back for such means. In carrying out my invention a selected, predetermined area 45 of the base 10 is coated with a thermoplastic, waterproof stiffening cement or glue 11, which serves, as will hereinafter appear, to render the coated area of the fabric sufficiently stiff to retain and preserve certain impressions formed 50 thereon. The cement 11 also serves to secure a legend bearing display panel 12, hereinafter described, to the fabric base.

A light reflecting surface is formed on the 55 coated area, except the marginal portions thereof, by covering such area with a layer of metal

foil 13, or which may be produced by painting or spraying the desired area with metallized lacquer, in which instance a suitable stencil may be employed to protect the fabric and marginal portions of the coated area not intended to be 60 covered. The coated portion of the fabric is next introduced between suitable die parts, not shown, where heat and pressure are simultaneously applied, to form regularly distributed, nodular impressions 14 and at the same time to cause 65 the thermoplastic cement to penetrate the fibres of the backing material 10 and the light reflecting material to adhere more firmly to the fabric.

Fig. 2 illustrates the backing member 10 as it appears subsequently to the aforementioned die 70 forming operation. The nodular, light reflecting area, is bordered by a strip 15 of the adhesive material above referred to, which serves marginally to secure the display panel 12 to the backing 10, and to form a moisture- and dust-proof 75 junction therebetween.

The display panel 12 is produced by stamping or cutting a sheet of flexible, translucent material, preferably of colored celluloid, to the desired shape, and producing the desired legend 80 or characters thereon by stenciling with opaque paint. The color of the opaque portions of the display panel (indicated at 16, Figs. 3 and 4) is preferably such as contrasts markedly with the color of the material constituting the panel. For 85 example, if the display panel is formed of ruby, or amber celluloid, the legend, design or characters may be produced in black paint.

The panel 12 is positioned over the backing 80 member 10 in registration with the cement coated area and the assemblage placed between suitable die-blocks. Heat and pressure are applied to the margins of the display panel and backing member 10 causing such members to become 95 bonded together through the agency of the thermoplastic cement bordering the light reflecting area. In the aforementioned die-pressing operation the margins of the central display area of panel 12 are preferably struck inwardly as indicated at 17 to provide an offset border or frame 100 which enhances the appearance of the display. If the display panel is formed by a stamping operation, offsetting of the marginal or framing portions of the panel may be accomplished in such operation.

If desired, the display panel may be attached to the mounting back, and nodular impressions formed in both members in a single operation, producing a display illustrated in the sectional view of Fig. 5. In carrying out this method, a 110

layer of thermoplastic cement is applied to the backing member as above described. The layer of light reflecting material may be applied over the cement surface or to the inner surface of the display panel. With the display panel positioned in registering relation over the coated surface of the mounting back, the assemblage is introduced between embossing dies, which are operated to form the nodules or protuberances 14 in the assembled structure and at the same time to fasten the display panel to the backing.

Obviously, numerous variations of the method described may be resorted to without departing from the invention, the essential characteristics 15 of which are set forth in the following claims.

I claim:

1. The herein described method of manufacturing signs, comprising covering a definite, predetermined area of a piece of fabric, constituting 20 a backing for the sign, with a thermoplastic adhesive and stiffening material, in coating all except the margins of said impregnated area with light reflecting material, in covering the entire impregnated area with a masking plate having 25 translucent characters, and in embossing the assembly and simultaneously causing the masking

plate to adhere to the fabric backing by the application of heat and pressure in suitable dies.

2. The herein described method of forming a display on a fabric base, which consists in coating a selected area of the base with thermoplastic cement, spraying the coated area with metallized lacquer to produce a light reflecting surface thereon, embossing the coated area, positioning a legend bearing display panel over the coated area, and applying heat and pressure to the marginal portions of the display panel to secure it to the fabric base through the agency of the thermoplastic cement.

3. The herein described method of manufacturing signs which consists in impregnating a definite predetermined area of a piece of fabric with a thermoplastic stiffening material, in coating all except the margins of said impregnated area with light reflecting material, in embossing said coated area by means of pressure, in suitable embossing dies, in covering said embossed area with a masking plate, and causing said masking plate to adhere to the uncoated marginal portions of said impregnated area by application of heat and pressure.

EDWARD L. FUCHS.
